UNITED STATES PATENT OFFICE.

KARL SCHRANZ, OF ELBERFELD, AND CLEMENS LUTTER, OF BARMEN-LANGENFELD, GERMANY, ASSIGNORS TO WINTHROP CHEMICAL COMPANY, INC., OF NEW YORK, N. Y.

1-ALKOXYMETHYL-3,7-DIMETHYLXANTHINES.

No Drawing. Application filed February 19, 1926. Serial No. 89,413, and in Germany May 23, 1925.

In our earlier application Ser. No. 41,870 (now Patent No. 1,616,282) filed July 6, 1925, the hitherto unknown 1-methoxymethyl-3,7-dimethylxanthine is described which acts like caffeine on the human body.

We have now found that also the higher homologues having most probably the formula

R standing for an alkyl other than methyl, possess diuretic properties. They form 15 double salts with organic acid salts. Together with a salicylate solution they furnish neutral solutions for subcutaneous use.

In order to illustrate the new process more fully the following example is given, the 20 parts being by weight:—

A mixture of 200 parts by weight of theobromine (sodium salt), 200 parts by weight of benzene and 105 parts by weight of chloromethyllethylether $\text{Cl}-\text{CH}_2-\text{OC}_2\text{H}_5$ is 25 heated in an autoclave during 5 hours to 120° C. The 1-ethoxymethyl-3,7-dimethylxanthine is isolated by extraction with benzene and crystallized from water. It crystallizes in needles melting at 152–153° C.

30 Other caffeine ethers may be produced in this way from theobromine salts e. g.

1-isopropoxyethyl-3,7-dimethylxanthine melting point 107–108° C.

1-n-propoxyethyl-3,7-dimethylxanthine 35 melting point 130–132° C.

1-n-butyloxyethyl-3,7-dimethylxanthine melting point 102–103° C.

1-isobutyloxyethyl-3,7-dimethylxanthine melting point 128–129° C.

1-benzyloxyethyl-3,7-dimethylxanthine 40 melting point 95–97° C.

1-allyloxyethyl-3,7-dimethylxanthine melting point 108–110° C.

We claim:

1. The process of producing 1-alkoxymethyl-3,7-dimethylxanthines, which process consists in treating a theobromine salt with chloroalkylether having most probably the formula: ClCH_2-OR R standing for an alkyl group containing two or more carbon 50 atoms, substantially as described.

2. The process of producing 1-ethoxymethyl-3,7-dimethylxanthine, which process consists in treating a theobromine salt with chloromethyllethylether, substantially as described.

3. The herein described 1-alkoxymethyl-3,7-dimethylxanthines having most probably the formula

in which R denotes an alkyl group containing two or more carbon atoms, being crystalline products forming double salts with salts of organic acids and possessing diuretic properties, substantially as described.

4. The herein described 1-ethoxymethyl-3,7-dimethylxanthine crystallizing from 70 water in the shape of needles melting at 152–153° C. forming double salts with salts of organic acids and possessing diuretic properties, substantially as described.

In testimony whereof we have hereunto 75 set our hands.

KARL SCHRANZ.
CLEMENS LUTTER.
